UNITED STATES PATENT OFFICE.

NILS NILSSON, OF NEW YORK, N. Y., ASSIGNOR TO THE NILSSON POWER COMPANY, OF NEW YORK.

MOUNTING ROTARY DRIVING AND DRIVEN MEMBERS.

SPECIFICATION forming part of Letters Patent No. 642,918, dated February 6, 1900.

Application filed September 29, 1898. Serial No. 692,174. (No model.)

To all whom it may concern:

Be it known that I, NILS NILSSON, a citizen of the United States, residing in New York, (Brooklyn,) in the county of Kings and State 5 of New York, have invented certain new and useful Improvements in Mounting Rotary Driving and Driven Members, of which the following is a specification.

This invention relates to the mounting of rotary driving and driven members, and especially to the mounting of a turbine wheel adapted to be rotated by a jet or jets of fluid to turn the wheel and produce power; and the invention has for its main object the supporting of the driven member or wheel on a rotary driving member in such a manner that the driven member will be capable of movement in a direction transverse to the axis of the driving member whenever any undue 20 stress tending to rotate or otherwise move the wheel is exerted upon the latter.

The mounting illustrated herein and forming the principal feature of the subject-matter of this invention is in the nature of an 25 improvement upon the general class of flexible mountings for turbine wheels which are rotated at a high velocity, and particularly as an improvement upon the construction shown, described, and claimed in my prior 30 application, Serial No. 626,805, filed March 10, 1897.

In the drawings accompanying and forming part of this specification, Figure 1 is a sectional side elevation illustrating my present 35 improvements applied to a turbine-motor of the type illustrated in my prior application hereinbefore referred to, parts of the wheel-inclosing casing and other members of the apparatus not essential for the illustration 40 of the present invention being indicated in dotted lines. Fig. 2 is an end elevation of the turbine wheel as seen from the left in Fig. 1, its connection with the driving member or shaft being indicated by dotted lines. 45 Fig. 3 is an enlarged transverse section illustrating the principal features of this improved mounting, the section being taken in line 33, Fig. 4, looking in the direction of the arrow. Fig. 4 is an enlarged central longitudinal section of the same, the section being taken on a line corresponding to line 44,

Fig. 3, and looking in the direction of the arrow; and Fig. 5 is a perspective view of a detail which will be hereinafter described.

Similar characters of reference designate 55 corresponding parts in all the figures of the drawings.

As to the principal feature of the present improvements, this may be embodied in any type of mechanism where a wheel or other 60 similar member is to be driven at a high speed by a rotary member or shaft; but as it is especially applicable to the mounting of turbine wheels of steam or other similar turbines it is illustrated herein in connection 65 with such a rotary driven member.

The driven member or wheel may be of any suitable construction, a proper one for the purpose being indicated herein by T, although it should be understood that any wheel or 70 similar driven member may be employed, provided it has a journal-opening of some-what greater diameter than the diameter of the corresponding member by which it is to be rotated.

A driving member suitable for the purpose of turning the wheel T is shown herein at S and will preferably embody a shaft, such as s, of the same diameter throughout, and a pair of bearing-blocks, such as b, fixed to the 80 shaft s in such positions as to permit the placing of the wheel (and certain other members to be hereinafter described) between such blocks before the second block is keyed fast or otherwise secured to the shaft. Each of 85 these blocks may be formed in a single piece or else may be of composite construction for a purpose hereinafter fully set forth, both of these blocks, however, being preferably so constructed as to be interchangeable and also 90 properly support the yielding holding means by which the driven member will be carried directly. In the present case, as in my prior application hereinbefore referred to, this driven member will be carried by one or more 95 yielding holding members or springs; but instead of supporting the wheel in such a manner that the hub thereof engages both ends of the yielding member or spring, as in the former case, I prefer to mount the driven member or wheel at a point relatively remote from one end of a suitable yielding device or spring 100.

and preferably between and at a considerable distance from the ends of such device. In the improved construction this mounting of the driven member at a point remote from 5 one end and preferably in the middle of a long and usually straight spring, such as a rod-spring, results in maintaining the driven member or wheel more perfectly in a definite plane, which is of course that plane exactly 10 perpendicular to the axis of the driving-shaft in which the driven member should always rotate in order to utilize the force of the driving medium or fluid to the best advantage and avoid unevenness of action due to wabbling 15 and other causes. In the preferred construction the yielding holding-springs will be cylindrical rod-springs, such as 2, it being desirable to employ a plurality of these springs disposed in parallelism with and preferably 20 equidistant from one another.

For the purpose of supporting the driven member on the yielding holding means the latter may pass into an opening in the side face or cheek of the driven member; but usually 25 this opening will extend entirely through the driven member transversely, and the holding means or springs will then of course also pass entirely through such driven member or wheel and form a direct support located 30 within the wheel itself. The opening or transverse bore in this driven member will ordinarily be substantially of the same diameter as the rod to be passed therethrough, and the latter may fit somewhat snugly in order to 35 prevent tipping or wabbling of the wheel, it being evident that when the wheel is supported in this manner at the center of a long elastic rod or rod-spring the movements of all points near the center of such rod-spring will 40 be substantially equalized and the wheel will move transversely relatively to the driving member or shaft in a definite plane, which is its proper plane of rotation. Moreover, the wheel will not tend to tip sidewise, as is the 45 case sometimes when the spring or springs are of the same length as the hub of the driven member or wheel to be supported.

In the preferred construction each of the blocks *b*, forming part of the driving member, 50 has one or more openings, corresponding in number to the number of springs used, tapering away from the driven member and serving to receive and locate the springs. These 55 openings are indicated by 5, and at their outer ends are substantially of the same diameter as the springs or rods 2, which latter may be supported loosely at at least one end and will preferably be merely inserted into place in a 60 pair of oppositely-disposed tapering openings 5, it being apparent that when each hub has these tapering openings or bores the bores of each pair should be alined with each other. In this case there are six bores in each block 65 *b*, these bores corresponding to the number of rod-springs 2 employed.

For the purpose of preventing rotary movement of the driven member *T* relative to the

driving member I may organize the driving and driven members in any manner suitable for the purpose; but in the preferred construction each of the blocks *b* will have a separable member or head, such as the annular disk 10, and this will have transverse openings therein corresponding substantially in size, as well as in position, to the openings 5 75 in the main portions of the blocks. These openings in the head 10 are indicated by 5' and will preferably be so shaped that each will have a straight guide-wall 5", so positioned that two opposite guide-walls at different sides of the axis of the head 10 will be parallel with each other and will engage opposite sides of two opposite rod-springs, as will be clear by referring to Fig. 3, this organization 80 of the driving member and the springs, which latter, as before stated, are fitted snugly into the driven member, serving to prevent turning of the driven member with respect to the driving member.

The heads or disks 10 may be secured to 90 their respective blocks *b* in any suitable manner—as, for example, by dowel-pins 6 on the head, these pins fitting into corresponding sockets or pin-holes in the adjacent faces of such blocks. The exposed faces of these 95 heads 10 form in this instance cheeks coöperative with the adjacent cheeks of the hub of the driven member or wheel *T* and serve to position the latter, although of course it should be understood that to provide for 100 proper flexibility of the connection between the driving and driven members a slight space should be left between each cheek of the driven member and the adjacent cheek of the driving member, this being clearly shown in 105 Figs. 1 and 4.

In a mechanism of the type hereinbefore described it is desirable to rotate the driving member in a given path and to locate it so that it will have no endwise play while turning. For this reason some means should be employed for locating the driving member or shaft in its proper position and for taking up 110 wear between its bearing-cheeks and those of the bearings in which it is supported. Hence 115 at least one of the two bearings in which the shaft will usually be mounted for rotation should embody means for adjusting the driving member or shaft longitudinally of its axis and for holding it positively in such adjusted 120 position.

In the construction illustrated the driving member is supported for rotation in a pair of bearings at least one of which is fixed, these 125 two bearings being indicated herein by *B* and *B'*. The bearing *B* will in this instance embody an outer or fixed bearing 20, in which will be movably supported an adjustable bearing 21, which may be shifted toward one of the blocks *b* to locate the driving member 130 positively longitudinally, it being evident that when this adjustable bearing is moved inward, as may be necessary from time to time, it will also serve to take up any wear

between opposing bearing-cheeks. In the construction shown the adjustable bearing 21 is externally screw-threaded, and its threads 21' engage corresponding internal threads 20' of the fixed bearing, the adjustable bearing usually being in the form of a sleeve and supporting at its outer end a suitable stop and closer for closing the end of the bearing and for engaging a transverse face of the driving member or shaft and helping to locate the latter longitudinally. This stop and closer may advantageously be a screw-plug, such as 22, adjustable in the outer end of the adjustable bearing and fitting internal screw-threads of the latter, it being clear that when the screw-plug is turned into the adjustable bearing far enough it may be brought into engagement with the outer end of the reduced portion or shaft proper of the driving member. This bearing just described will usually be suitably bushed, a bushing of Babbitt metal or similar material, such as 23, being indicated for this purpose, and in order to hold the bushing in place the adjustable bearing may carry an annular stop at its inner end, such as the annular externally-threaded ring or nut 24, which also serves to prevent the escape of the soft metal when the bushing is heated up during the rotation of the shaft. A washer, such as 25, may be interposed between the outer cheek of the co-operating block *b* and the adjacent cheek of the bearing *B*.

By means of a bearing such as that illustrated herein the driving member may be located positively in longitudinal direction and the proper cheek thereof may be maintained always in contact with the cheek of the adjustable bearing member 21, even though such cheek of the driving member may not always be in contact with that of the fixed bearing member 20. Moreover, the screw-plug 22 will serve as an additional means for positively locating the journal member or shaft longitudinally, as it also may be adjusted to follow and engage the end of the shaft as wear is taken up from time to time, it being clear that this adjustment of the screw-plug will also result in forcing the bushing into position to abut against the stop-collar 24 and fill the space between said stop and the screw-plug.

By means of the devices hereinbefore described a turbine wheel, and especially one of the type intended to be rotated at a high speed by one or more steam-jets, may be positively located for rotation in a definite plane on a suitable driving member, while free to yield radially when any abnormal stress is exerted thereon, and the driving member may also be located positively at all times in longitudinal direction between two opposite and aligned bearing-cheeks to obtain the highest efficiency when the wheel is started rotating.

Having described my invention, I claim—

1. The combination, with a rotary driving

member, of a plurality of separate springs carried by said driving member and disposed longitudinally of the axis thereof, and each 70 separately movable independently of the others at every point that is in contact with the driven member, and a rotary driven member supported by said springs at a point relatively remote from corresponding ends of 75 such springs.

2. The combination, with a rotary driving member, of a plurality of normally-parallel separate rod-springs carried by said driving member and disposed longitudinally of the 80 axis thereof, and each separately movable independently of the others at a point that is in contact with the driven member, and a rotary driven member supported by said rod-springs at a point relatively remote from corresponding ends of 85 such springs.

3. The combination, with a rotary driving member, of a plurality of rod-springs carried by said driving member and disposed longitudinally of the axis thereof and loosely supported at their ends for longitudinal movement relative to one another when tensioned near their centers, and a rotary driven member supported by said rod-springs at a point relatively remote from the corresponding 95 ends of such springs.

4. The combination, with a rotary driving member having a bore tapering away from the driven member and disposed longitudinally of the axis of the driving member, of a 100 spring loosely supported at one of its ends in such tapering bore and movable longitudinally therein when tensioned near its center and also supported at its other end, and a rotary driven member supported by said spring. 105

5. The combination, with a rotary driving member having aligned separated bores tapering away from the driven member and disposed longitudinally of the axis of the driving member, of a spring loosely supported at 110 its ends in such tapering bores and movable longitudinally therein when tensioned near its center, and a rotary driven member supported by said spring.

6. The combination, with a rotary driving member having a circuit of sets of aligned separated bores tapering away from the driven member and disposed longitudinally of the axis of the driving member, of rod-springs supported at their ends in such tapering 120 bores, and a rotary driven member supported by said rod-springs.

7. The combination, with a rotary driving member, of a rotary driven member having transverse bores, and a plurality of separate 125 rod-springs carried by said driving member and disposed longitudinally of the axis thereof and passed through the bores in the driven member and supporting the latter at a point relatively remote from the corresponding 130 ends of such springs, and each separately movable independently of the others at every point that is in contact with the driven member.

8. The combination, with a rotary driving member having guide-openings disposed at opposite sides of its axis, said guide-openings having parallel walls, of a pair of springs located at different sides of, and disposed longitudinally of, the axis of such driving member, and normally in contact, respectively,

at their opposite sides with said respective guide-walls, and a rotary driven member supported by said springs.

NILS NILSSON.
